CLAIM

We claim the ornamental design for a funnel, as shown and described.

DESCRIPTION

FIG. 1 is a front perspective view of a funnel;

FIG. 2 is a rear perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and,

FIG. 8 is a right side view thereof.

The broken lines in the figures illustrate portions of the funnel that form no part of the claimed design.
